UNITED STATES PATENT OFFICE

JOHN F. PETERS, OF ROCHESTER, NEW YORK, ASSIGNOR TO AMERICAN CAN COMPANY,
OF NEW YORK, N. Y., A CORPORATION OF NEW JERSEY

COMPOUND LINING MACHINE

Application filed September 26, 1927. Serial No. 222,025.

This invention relates in general to a compound lining machine for can ends, and has more particular reference to a continuously operating machine in which the lining compound is applied by means of a roller to a die which passes over the roller, the die directly transferring a gasket of the compound to a can end.

In the manufacture of a sanitary tin can of commerce the end seams of the can are provided by flanging the can body and offsetting the edge of the can end to provide a companion flange and interfolding and pressing these flanges together to form an hermetic seal, gasket material is interposed between them in the form of a film of desired thickness upon the can end flange.

This invention contemplates the provision of a gasket material upon a die adapted to engage about the shoulder of the can end formed in offsetting to provide the flange and to deposit on this flange a formed liner of semi-solid gasket material or compound which is received from a roller running in a supply of the material.

An important object of the invention is the provision of an apparatus for thus applying the gasket which will arrange the material upon the can end flange with minimum movement or disturbance of the die after it receives its charge.

An important object of this invention, therefore, is in the provision of continuously operable carriers for the can ends and dies which register in vertical alignment and are relatively movable to apply a gasket directly from a die which receives the compound to a can end placed below it.

A further important object of the invention is in the provision of a die fixed against rotation upon its own axis and moved without interruption over a roller which applies lining compound to the entire die surface without independent rotation thereof.

A further object of the invention is in the provision of a die moved without independent rotation about a vertical axis and fixed in height, to which lining compound is applied, and thereafter a can end to be lined

is raised without interrupting the movement of the die about the axis.

A still further object of the invention is in the provision of a lining die supported by a continuously moving carrier, which engages a compound applying roller to receive a gasket in axial alignment with a can end subsequently positioned and later moved relatively to receive the lining gasket from the die.

Numerous other objects and advantages of the invention will be apparent as it is better understood from the following description, which, taken in connection with the accompanying drawings, discloses a preferred embodiment thereof.

In the drawings:

Figure 1 is a plan view of the compound lining machine of this invention;

Fig. 2 is a sectional plan of the driving gears taken on a line 2-2 of Fig. 3;

Fig. 3 is a composite sectional view taken on a line 3-3 of Fig. 1;

Fig. 4 is a transverse section of the can end feeding mechanism taken on the line 4-4 of Fig. 1;

Fig. 5 is a detail section of the compound applying mechanism taken on the line 5-5 of Fig. 1;

Fig. 6 is a detail section of the compound applying mechanism taken on a line 6-6 of Fig. 1;

Fig. 7 is a sectional view illustrating the application of lining compound from a die to a can end, as taken along the line 7-7 of Fig. 1;

Fig. 8 is a fragmentary section illustrating the can end discharging mechanism, as taken along a broken line 8-8 of Fig. 1; and

Fig. 9 is a detail elevation of the upper end connection of an ejector rod.

In carrying out this invention, can ends are separated from the bottom of a stack, picked up one at a time by a rotating feeding turret and delivered continuously to can end supports in a rotating carrier disposed below raised lining dies. After a rotatable compound applying roller engages the entire lining surface of the die without independently rotating it, the positioned can end is raised

toward the die, lined with a gasket, stripped from the die, moved downwardly and stripped from the can support. A discharge turret then engages and continues the movement of the lined can end, delivering it to a conveyor for further operations.

Referring more particularly to the drawings, a supporting frame 20, in the form of a housing, is mounted on a base 21, and has an intermediate web 22 and a top horizontal table 23. The driving mechanism contained within the housing comprises a horizontal drive shaft 24 driven by a sprocket 25 secured to the shaft, and a drive chain 26, which also engages a sprocket 27 secured to the rotor shaft 28 of a motor 29.

A worm 30 carried by drive shaft 24 meshes with a worm gear 31 secured to the lower end of a vertical shaft 32 journalled in bearings 33 and 34 formed in a gear casing 35 secured to the under side of the web 22 and in a bearing 36 formed in the web and the bearing 37 formed in the table.

Directly above the bearing 36 in the web 22, a spur gear 38 is keyed to the shaft 32, which has an upwardly extending hub 39 with a bevel gear 40 meshing with a bevel pinion 41 at the end of a stub shaft 42 journalled in bearing 43 of the housing. The opposite end 30 of the stub shaft 43 carries a bevel gear 44 which meshes with a bevel pinion 45 on a vertical stub shaft 46 journalled in a bearing 47 of the housing. At the upper end of shaft 46 is a can end separating device comprising a cut-out disc 48 with a spiral groove 49 which engages the periphery of the lowermost can end 50, which is held within a magazine 51. The can ends 50 are formed with vertical shoulders 50' to fit within the can bodies and with flanges 50" which are usually in the form of channels. The can ends are stacked in a magazine 51, which comprises supporting rods 52 mounted above the table 23. The stack of can ends 50 in the magazine extends above a can end feeding turret 53 secured to the upper end of shaft 32 and movable over the surface of the table 23. The turret 53 is provided with a series of can end pockets 54 (see Figs. 1 and 4) at the rear side 50 of which is a finger 55 extending up for engaging the lowermost can end separated from the magazine stack by the cut-out disc 48, this can end being then supported upon the disc 48 and upon a shoulder 56 at the opposite side 55 of the magazine, so that it may be swept around by the finger 55 in a circular path of travel in one of the pockets against an outer circular guide 57. The can ends are thus disengaged one at a time from the bottom of the stack and are fed successively in properly timed relation by the feeding turret 53.

From the feeding turret 53, the can ends are delivered successively without interruption to a rotatable carrier, which comprises a turret sleeve 60 surrounding a fixed bearing

post 61 secured to the web 22. The sleeve 60 is continuously rotated by means of a spur gear 62 secured to or formed integral with the lower end thereof and meshing with the spur gear 38 keyed to the shaft 32.

Projecting from the sleeve 60 is a spider section 63 having outer tubular bearing 64 in which can end supports 65 are feathered by keys 66 for vertical sliding movement.

Each can end 50 is delivered to a support 65, which comprises an enlarged head 66' (see also Fig. 7), which carries a cap end supporting plate 67 secured loosely to the head by a clamping block 68 with coil springs 69 seated in a recess in the head and interposed between the head and the plate 67 to permit a yielding of the plate.

Intermediate the ends of sleeve 60 it carries a perforated plate 70, the upper surface of which is flush with the table 23. Openings 71 are provided through the plate to permit movement of the can end supports 65 and the heads 67 therethrough, but the openings are not of sufficient size to permit the passage of can ends 50. As the can ends are fed by turret 53, they are slid over the surface of the plate 70 in engagement with the can end supports 65, and during the removal of the can end the upper surfaces of the plate 67 carried by the can end support 65 is flush with the upper surface of the plate 70, thus permitting a sliding movement of the can ends from the plate.

To raise and lower each can end support 65, a cam roller 72 is mounted at the lower end of each support 65 and is adapted to ride upon a cam surface 73 formed in a circular cam 74 arranged on the web 22 (Fig. 3). Since the cam is stationary and the can end supports 65 rotate with the carrier, each can end support is raised and lowered as the timed actions of the machine require.

Lining dies 75 corresponding in number to the can end supports 65 are mounted in alignment above the supports 65 and in bearings 76 at the outer ends of spider arms 77 projecting from the upper portion of the turret sleeve 60. In each bearing 76 there is a sleeve 78 vertically adjustable within the bearing by nuts 79 threaded on the upper and lower ends of the sleeve. The lining die 75 is threaded on or otherwise fixed to the lower end of the sleeve and is thus accurately adjustable in fixed position in its bearing 76. The die is annular in form so as to pass around the shoulder 50' of the can end.

The lower edge of the lining die receives a semi-liquid lining compound upon its lower annular surface, which conforms to the size and shape of the flange of the can end 50 to be lined, and subsequently transfers this ring of compound into the can end flange.

To apply a lining compound 80 to the lower surface of the die, a lining receptacle or tank 81 (see Figs. 1, 5 and 6) is secured on the up-

per surface of the table 23 and contains a continuously rotating roller 82 secured to one end of a horizontal shaft 83 journalled in a bearing 84 formed integrally with the tank 81. 5 This roller is supported between the die and the carrier. At its outer end, the shaft 83 carries a bevel gear 85 which meshes with a corresponding gear at the upper end of a vertical shaft 87 journalled at its upper end in the 10 frame of the tank 81 and in a bearing 88 formed in the web 22 at its lower end. A spur gear 89 secured (see also Fig. 2) to the shaft meshes with an idler gear 90 mounted on a stud shaft 91 secured to the web 22, and 15 this gear meshes with the driving gear 62 formed as a part of the turret sleeve 60. A continuous rotation is thus imparted to the roller 82 partially immersed in the compound 80, which raises a film of compound on the 20 surface of the roller gaged in thickness by the scraper plate 92 adjustable by screws 93.

As each die 75 is rotated by the turret sleeve 60 so that adjoining portions of the roll and die travel at like speed in the same direction, 25 the die moving tangentially to the roll, the annular lower surface of the die engages and passes over and across the upper surface of the roller 86, which applies an annular film or ring of compound of predetermined thickness to the die surface. The compound is applied just prior to the positions where the can end support 65 receives a can end 50 from the can end feeding turret 53.

The dies 75 remain fixed in their vertical 30 position as they are rotated by the carrier turret, and the can ends are moved toward and from their respective dies without interruption of the rotary movement. Just before a can end reaches the lining applying position, it is engaged and pressed firmly in engagement with the plate 67 of its support by means of a plate 94 secured to the lower end of a rod 95 movable slidably within sleeve 78 and carrying a block 96 (see Figs. 3 and 9) at 45 its upper end. This block carries a cam following roller 97 confined within a cam groove 98 of a stationary cam 99 secured to the upper end of the fixed support by a fastening nut 100, the sides of the block 96 having extensions 96' which engage the outer surface of the stationary cam 99 to prevent rotation of the rod 95. The upper edge of the plate 67 is preferably formed with a grooved edge or recess 101 for permitting the plate to engage 50 under the can end flange and within the central portion of a can end positioned upon the can end support, and when the support is raised with a can end thereon, the can end is first engaged and pressed firmly upon the 55 plate 67 against the yielding pressure of spring 69 by means of the plate 94. At this time the plate 94 is projected below its die 75, as clearly shown in Figs. 3 and 8.

A continuation of the movement of the carrier turret brings the can end 50 in engage-

ment with its corresponding die 75 to receive therefrom the lining compound, as shown in Fig. 7, and as the can end support is withdrawn from the die 75, it is first stripped from the die by an ejecting movement of the rod 95 and plate 94 downwardly, so that the lined can end will not adhere to the die. 70

A further rotary movement of the carrier turret carries the can end support downwardly due to its contact with the cam 73, until 75 the projecting edge of the can end 50 engages the perforation 71 in the plate 70, thereby stripping the can end from its support 65 and allowing the can end to rest on the upper surface of the plate 70. 80

A discharge turret 101' is mounted at the upper end of a shaft 102 (see Figs. 1, 2, and 8) and the shaft is rotated by a gear 103 which meshes with the gear 62 of the driving sleeve 60, so the turret is constantly driven in timed 85 relation to the lined can ends.

This discharge turret has can end pockets 104 and arms 105 to engage a lined can end 50 as it is moved in its circular path by the can end support 65, and one of the arms 105 engages behind the can end and sweeps it from the plate 70 across the surface of the table 23 against a circular guide rail 106 to a discharging position, where an opening 107 is provided in the table of sufficient diameter to permit the lined can end to fall through the table and upon a conveyor chain 108, which passes at one end over a sprocket 109 and moves in a discharge chute 110 for delivering lined can ends to a drier or to any other operating 100 mechanism, which is not shown. To insure the discharge of a can end from the pocket 104 of the discharge turret 101', a segmental 105 guide rail 111 mounted on the table 23 and forming an extension of the guide rail 106 is curved inwardly about a portion of the edge of the discharge opening 107. 105

All of the various operations take place in proper sequence without any interruption in the movement of a can end from the time it is fed from the magazine 51 until it is discharged upon the conveyor chain 108. The movement of the can ends is continuous, the machine containing a number of can ends, each being in a different stage of operation at 110 any particular time.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred 115 embodiment thereof. 120

I claim:

1. In a can end lining machine, a movable can end carrier, a movable die at a distance above the carrier, means extending between

the die and carrier for applying a lining compound to the die, and means for raising a can end from the carrier to receive the lining from the die.

5. 2. In a can end lining machine, a continuously rotatable die and can end carrier respectively having axes parallel with each other, means for applying a lining compound to the die while it is in motion, and
10 means for raising a can end to receive the lining compound from the die.

3. In a can end lining machine, a movable carrier for can ends, a die movable with the carrier, means for raising a can end from
15 the carrier to the die, and means arranged between the die and the carrier for applying a lining compound to the under surface of the die.

4. In a can end lining machine, a movable carrier for the can ends, a die raised relative to and also movable with the carrier, a lining compound tank, and a roller supported between the die and carrier for applying compound to the entire die surface as it moves
25 over the roller, and means for applying the compound from the die surface to a can end.

5. In a can end lining machine, a rotatable, multiple can end carrier for the can ends, lining dies movable with the carrier and
30 corresponding in number and position there-to, means between the die and carrier for applying a lining compound to the entire under surface of the die, and means for thereafter relatively moving the can end carrier and the die for applying a lining compound to a can end.

6. In a can end lining machine, a rotatable can end carrier, comprising movable heads, lining dies corresponding with the heads
40 and movable with the carrier, means for relatively moving the dies and heads, a gasket applying means interposed between the heads and dies at a portion of their travel, and means for thereafter relatively moving the die and its head for applying a can end to the die.

7. In a can end lining machine, a continuously movable carrier for corresponding can end heads and lining dies, of means for relatively moving the heads and lining dies as
50 they are moved by the carrier, a compound applying roller interposed between the dies and can end heads through a portion of their travel for coating the under surface of the die with a lining compound, means for thereafter moving corresponding dies and heads together, for applying the lining from the die to a can end, and an ejector for preventing a can end from adhering to the die when
55 the die and head are separated.

8. In a can end lining machine, a rotatable carrier, corresponding can end supporting heads and lining dies, movable relatively toward and from each other in the carrier, means interposed between the dies and

heads for applying a lining compound to the under surface of each die as it is moved by the carrier, means for moving each die and its head toward each other to apply a lining from the die to a can end supported by the
70 head, and an ejector movable from the die to disengage a can end when the die and head are thereafter moved apart.

9. In a can end lining machine, a continuously rotatable carrier, can end supports and lining dies therefor movable with the carrier, and independently movable toward and from each other, means arranged between the die and its can end carrier for applying a lining compound to the under surface of the
80 die as it is moved by the carrier, means for feeding can ends to the can end supports of the carrier, means for thereafter moving the can end supports and the dies together for applying a lining to the can ends, and means
85 for preventing a can end from sticking to its die when the can end carrier and die are moved apart.

10. In a can end lining machine, a continuously rotatable carrier, a plurality of can end supports and lining imprinting dies mounted therein for independent relative movement toward and from each other, means for feeding can ends separately in succession to the can end supports of the carrier,
90 means for moving the can end supports and dies toward each other for applying a lining to each can end and for thereafter moving them apart, and means for continuously discharging the lined can ends from the carrier
95 when the supports and dies are moved apart.

11. In a can end lining machine, a continuously rotatable carrier, a plurality of can end supports and lining dies movable with the carrier and relatively movable toward
100 and from each other in the carrier, means interposed between the supports and dies in a portion of their travel where they are spaced apart, for applying a lining compound to the under surface of the die, means for feeding can ends from a stack, one at a time, to said can end supports, means for moving each support and its die toward each other, for lining a can end therebetween and then moving them apart, and means for continuously discharging the lined can ends from the carrier.
110

12. In a can end lining machine, a rotatable carrier, a plurality of can end supports and lining dies mounted therein for independent relative vertical movement, means for feeding can ends to the supports, gasket lining means for engaging the under surface of the dies as they are moved by the carrier, means for relatively moving a die and its end support to apply lining from the die to a can end, an ejector for stripping a can end from the die when the die and support are thereafter moved apart, and means for stripping a lined can end from the carrier in discharging it.
120
125
130

13. In a can end lining machine, a continuously rotatable carrier, comprising a perforated plate, lining dies and can end supports mounted in the carrier for movement therewith and independently movable toward and from each other, means for continuously feeding can ends to the supports, means for applying a lining compound to the under surface of the dies, a cam for moving a die and its can end support relatively together for applying a lining to the can end, an ejector for stripping a can end from the die when the die and a can end support are moved apart, the support being moved through the perforation of the plate to strip a can end from the carrier when it is lined, and means for thereafter discharging a lined can end from the plate. 70
14. In a can end lining machine, a continuously rotatable carrier, can end supports and lining dies mounted in the carrier for movement therewith and for independent relative movement toward and from each other in lining a can end, and means for applying a lining compound to the under surface of each die when the die and its can end support are separated, said means comprising a compound tank being fixed in position and extending below the dies throughout a portion of their path of travel, and a roller continuously rotating in said tank for applying lining material to the under surface of each die as it passes thereover. 85
15. In a can end lining machine, a continuously rotatable carrier, can end supports and lining imprinting dies mounted therein and movable independently toward and from each other, a rotatable feeding turret, a positively driven cutout for feeding can ends one at a time from the bottom of a stack to the feeding turret, means for relatively moving the can end supports and dies in applying a lining compound thereto without interruption of movement of the carrier, means for disengaging lined can ends from the die and support, and discharging means for withdrawing lined can ends successively from the carrier. 90
16. In a can end lining machine, a rotatable carrier, can end supports and dies mounted for movement in the carrier and independently movable toward and from each other, means for feeding can ends to the supports in the carrier, compound applying means for engaging the die surface, and means for disengaging the can ends from the die and support, said disengaging means comprising an ejector movable relatively to each die and a fixed cam for engaging the ejector to move it in timed relation for stripping a can end from the die. 100
17. In a can end lining machine, a movable carrier, a can end support, and a lining die mounted in the carrier and movable relatively toward and from each other, means inter- 105
- posed between the support and the die at one portion of their path of movement for applying a lining compound to the under surface of the die, said means comprising a rotatable roller, a compound tank in which it is rotatable, and means for adjusting the thickness of the compound applied by the roller to the lining die. 110
18. In a can end lining machine, a movable carrier, a lining imprinting die supported by the carrier, means for applying a can end to the die, and removing it therefrom while the carrier is in motion, means for adjusting the die in the carrier, and means for applying fluid compound to said die. 115
19. In a can end lining machine, a movable carrier, a can end support mounted in the carrier for vertical movement therein, a plate with a grooved edge yieldingly held at the top of the support, means for feeding can ends to the plate at the top of the support and means for removing them therefrom, and a clamping plate for engaging a can end carried by the support and pressing it yieldingly over the grooved edge of the plate carried by the support. 120
20. The process of lining can ends which comprises providing a bath of lining compound, removing from said bath compound in the shape of a desired continuous liner and depositing same into the flange of a can end and at the same time conveying said can ends while the said liner is being applied thereto. 125
21. In a machine for applying compound to the flanges of can ends having shoulders, the combination of a source of lining material, a roll for removing material from said source, a die member passing across said roll and adapted to pass about the shoulder of a can end and apply lining material to the flange thereof. 130
22. In a machine for applying compound to the flanges of can ends, the combination of a source of lining material, a roll receiving lining material from said source, a die member passing across the said roll, moving in the direction of the rotation of said roll and receiving lining material therefrom, said die member being adapted to pass about the shoulder of a can end and apply lining material to the flange thereof. 135
23. In a machine for applying compound to the flanges of can ends, the combination of a supply of lining material, a roll receiving material from said supply, a die movable tangentially with respect to said roll and first receiving the lining material on its bottom at a point of the circumference of the die and thereafter arcuately in both directions of said point to receive lining material on the full lining portion of said die, said die being formed to pass about the shoulder of a can end and apply lining material to the flange thereof. 140

24. In a machine for applying compound to the flanges of can ends, the combination of a supply of lining compound, a roll receiving lining material from said supply, a die for transferring lining material from said roll to said can end, means causing said die to pass over said roll, adjoining portions of the said roll and said die travelling at like speed and in the same direction, said die being shaped to pass about the shoulder of a can end and apply lining material to the flange thereof.

10 25. In a machine for applying compound to the flanges of can ends, the combination of a source of lining material, a continuously moving device receiving material from said source, a continuously moving die receiving material from said device and formed to pass about the shoulder of a can end and depositing said material to a flange thereof and a can carrier moving with the die.

15 26. In a machine for applying compound to the flanges of can ends, the combination of a source of lining material, a roll receiving lining material from said source, a die carrier moving said die from said lining material receiving position to liner applying position, and a die fixed against movement relative to said die carrier for receiving said material 20 and applying the same to the flange of said can end, and a can end carrier moving with and to and from said die.

25 27. A gasket lining machine, comprising means for delivering flanged covers having shoulders at the inner parts of their flanges, to a lining station and a die member shaped to pass about the shoulder of the can end and to deposit compound in the shape of a continuous liner upon the flange about said shoulder, and a roller for applying fluid compound to the bottom of said die member.
